UNITED STATES PATENT OFFICE.

ADOLPH SAMETZ, OF NEW YORK, N. Y.

DESIGN FOR A BUTTON-HOLDER.

SPECIFICATION forming part of Design No. 30,079, dated January 31, 1899.

Application filed December 22, 1898. Serial No. 700,068. Term of patent 7 years.

To all whom it may concern:

Be it known that I, ADOLPH SAMETZ, of the city of New York, borough of Manhattan, in the county of New York and State of New York, have invented and produced a new and original Design for a Button-Holder, of which the following is a full, clear, and exact description.

Reference is to be had to the accompanying drawings, forming a part of this specification, in which—

Figure 1 is a face view of a button-holder, showing my design; and Fig. 2 is a section on the line 2 2 of Fig. 1.

15 My design consists in a base-board, on the

face of which appears a series of T-shaped openings, the upper or horizontally-disposed portions of which terminate in eyelet-like openings. The corners at the junction of the vertical and horizontally-disposed portions of the openings are curved outward, as plainly shown in Fig. 2.

I claim—

The design for a button-holder herein shown and described.

ADOLPH SAMETZ.
